UNITED STATES PATENT OFFICE.

WILLIAM C. PEET, OF NEW YORK, N. Y., ASSIGNOR TO THE J. L. MOTT IRON WORKS, OF SAME PLACE.

DESIGN FOR A LAVATORY-BASE.

SPECIFICATION forming part of Design No. 32,857, dated June 19, 1900.

Application filed April 21, 1900. Serial No. 13,812. Term of patent 7 years.

To all whom it may concern:

Be it known that I, WILLIAM C. PEET, a citizen of the United States, residing at the city of New York, in the county and State of New York, have invented and produced a new and original Design for a Lavatory-Base, of which the following is a specification, reference being had to the accompanying drawings, forming a part thereof, in which—

10 Figure 1 is a perspective view, and Fig. 2 is an elevation, of the lavatory-base.

The general configuration is circular and, as shown in the drawings, the leading or essential features are the parallel-sided fluted portion and the top and bottom molded portions.

15 The flat bottom *a* is circular and of more extended area than the flat circular top *b*. The lavatory-base is provided with parallel sides *c*, and in the shaft are vertical flutes *d*.

The design of the lower part of the base or

pedestal comprises the rib *e*, with a vertical face, the adjacent ogee molding *f*, the coves or recesses *2 3*, the convex molding *g* above the cove *2*, the rib *h* above the molding *g*, and *25* the bead *i* adjacent to the parallel sides *c* and above the cove *3*.

The design of the top of the base or pedestal comprises the rib *k* with a vertical flat face, the smaller under rib *l*, the ogee molding *m* *30* beneath the same, and the rib *n* beneath the ogee molding and adjacent to the parallel sides *c*.

What I claim is—

The design for a lavatory-base, substantially as shown and described.

Signed by me this 2d day of April, 1900.

WILLIAM C. PEET.
